UNITED STATES PATENT OFFICE.

ELIZA A. MURDOCK, OF BOSTON, MASSACHUSETTS.

DESIGN FOR A SKATING OR RIDING CAP FOR LADIES.

Specification forming part of Design No. 1,146, dated September 20, 1859.

To all whom it may concern:

Be it known that I, ELIZA A. MURDOCK, of Boston, in the county of Suffolk and State of Massachusetts, have invented a new and useful Design for Riding and Skating Caps for Ladies, Misses, and Children; and I do hereby declare that the same is fully described and represented in the following specification and the accompanying drawings, of which—

Figure 1 represents a side view of my improvement. Fig. 2 is a top view, and Fig. 3 a front view, of the same.

By referring to the said drawings it will be seen that my design consists in constructing the cap A with twelve or any other suitable number of gores, and with a raised band, B, running around the lower portion of the cap, as seen in the drawings. I also place two ear-pads, C, on each side of the cap, below the

said band, and I place two tassels to hang over the said ear-pads. On the central top part of the cap I place a crochet ornament, as seen in Fig. 2.

What I claim is—

The design, as above described, and as shown more particularly in the drawings, of a cap for ladies, misses, and children, the same to be made of Berlin or Shetland worsted or any other suitable material capable of being knit into the form as above described.

In testimony whereof I have hereunto set my signature this 31st day of August, A. D. 1859.

ELIZA A. MURDOCK.
